UNITED STATES PATENT OFFICE.

EDWARD HOLMES, OF BUFFALO, NEW YORK, ASSIGNOR TO E. & B. HOLMES, OF SAME PLACE.

IMPROVEMENT IN HOOP-DRIVING AND BARREL-CROZING MACHINES.

Specification forming part of Letters Patent No. 37,719, dated February 17, 1863.

To all whom it may concern:

Be it known that I, EDWARD HOLMES, of the city of Buffalo, and State of New York, assignor to Edward Holmes and Britain Holmes, composing the firm of E. & B. Holmes, of the city of Buffalo aforesaid, have invented a new and Improved Hoop-Driving and Barrel-Crozing Machine; and I do hereby declare that the following is a full and exact description of the construction and operation of the same, reference being had to the accompanying drawings, making a part of this specification, in which—

Figure I is a side elevation. Fig. II is a vertical section. Fig. III is a top plan. Fig. IV is a plan of a device for expanding and contracting the drivers.

Letters of like name and kind refer to like parts in each of the figures.

A represents the main frame-work of the machine.

B represents the drivers. There are six of these drivers, (may be more or less,) which are hinged to the head-piece C, as shown at C', so that they may flex or yield back when driving the hoop sufficiently to follow the bilge of the barrel. Each driver has a hook on its upper end, as shown at C², for hooking on the truss-hoop. These drivers are twice or more the length of the barrel, and pass through slots in the ends of the expanding and contracting arms D. The arms D are pivoted to the disk D', as shown at d², so that by turning the disk the arms will be thrown outwardly, as shown on Fig. IV, and drawn inwardly as represented by the red dotted lines, Fig. IV, and thereby expand and contract the drivers as required. One or two of the slots may be left open, as shown at d³, in order to allow the driver to fall beyond the arm, in order to make plenty of room to put a barrel in between the drivers and to take it away when the hoops are driven.

E represents a vertical screw, which is caused to revolve by means of the bevel-gear E', fixed to its upper end, and the bevel driving-pinion F, placed on shaft F', which meshes therewith. This screw runs in a stationary head-block, G, at the bottom and a stationary head-piece, H, at the top. The head-block G is supported by the rods or hangers I, which drop down from the upper part of the main frame. The head-piece C, to which the drivers are hinged, has a female screw cut therein corre-

sponding to the vertical screw E, so that as the vertical screw E revolves the head-piece C, and with it the drivers, will be run up or down, as required, and the drivers being hinged or jointed to the head C, renders them flexible or yielding in the direction to follow the bilge of the barrel as the hoop is driven on.

J is an annular open-bed table, upon which the barrel or cask is placed for driving the hoops and for crozing. The opening through this bed-table is of the size or a little larger than the end of the barrel or cask, so that the end of the barrel or cask will pass in and bring the ends of the staves upon the ring K, the truss-hoop resting upon the annular table and the end of the staves upon the ring.

L is a double wedge, for supporting the ring K when in place, as shown in Figs. I and II.

When the barrel is put into the machine for driving the hoops, the ends of the staves will rest upon this ring and the truss hoop will rest upon the annular table J. When the hoops are driven, this wedge is withdrawn sufficiently to allow the ring K to fall away from the staves, in order to form sufficient room for the free working of the crozing and chamfering and howeling tools, as shown in Fig. II, and as hereinafter more fully explained. I do not limit myself to the use of this wedge, as other equivalent devices may be used for the same purpose.

M represents a tool-head, which supports the chamfering, crozing, and howeling tools. This tool-head revolves within the opening of the bed plate J. The chamfering-tool is by means of its holder n' connected to one end of this head, and is represented at m', and the howeling and crozing tools are by means of their holder n' connected to the other end the howeling-tool is shown at m², and the crozing-tool at m³. These tools are of common construction. A jointed arm, O, connects with each tool-holder and with the cross-head P. These are jointed to the tool-holder, as shown at p', and to the cross-head as shown at p². This cross-head rests upon and revolves upon the top of the vertical shaft Q, which shaft has a vertical movement for the purpose of controlling the depth of the cut of the chamfering, crozing, and howeling tools, but it does not revolve. A vertical movement is given this shaft as follows: A screw-thread is cut upon its lower end, and a bevel-wheel nut, R, placed thereon, which bevel-wheel nut meshes with the bevel-

pinion s , which bevel-pinion is placed upon the end of the inclined shaft s' , so that the operator by turning with his hand the shaft s' will cause the wheel-nut R to revolve in either direction he pleases, and thereby raise and lower the shaft Q , as required. The depth of the cut of said tools (graduated at each revolution of the cutter-head) is thereby easily controlled by the operator while the machine is in motion. The rising of the shaft will draw the tool-holders and the tools inwardly, and the lowering of the shaft will throw them outwardly—the chamfering-tool moving on an incline corresponding to the incline of the chamfer, and the crozing and howeling tools and tool holder moving horizontally. The vertical shaft Q passes through the hollow shaft P , upon which hollow shaft the tool head M is supported. The lower end of this shaft has a bearing in the head-piece H . It also has a bearing near its upper end in the bridge u .

V is a pulley, fixed on the hollow shaft T , which connects by belt to the driving-pulley V' .

W is the main driving-shaft. w' and w^2 are friction driving-wheels placed thereon.

X is a friction-wheel, fixed on the end of shaft F' , and is located between the two friction-wheels W' and W^2 .

The main driving-shaft W , with the friction-wheels and pulleys thereon, may be moved longitudinally back and forth at pleasure by means of a forked lever connected to one end thereof, or by any other convenient and common means, so that either one of the friction-wheels (W' or W^2) may be brought into contact with the friction-wheel X and revolve the shaft F' in either direction, and thereby run the drivers up or down at pleasure. There is space enough between the wheels W' and W^2 to allow of their being placed by a longitudinal movement of the shaft W so that neither will be in contact with the friction-wheel X .

Z is a tight pulley and Z' a loose pulley on shaft W .

Operation: The staves forming the barrel are, in the first place, set up with a truss-hoop on each end in a common manner. The drivers are then expanded by means of the expanding-arms D and disk D' . One of the drivers is released from the arm through the slot d^3 , and dropped down so as to make ample room to pass the barrel in and place it upon the annular table, the downward end of the staves passing into the annular table, so that the lower truss-hoop will rest upon the annular-bed table. The bilge truss-hoop is now put on, and the drivers contracted or drawn inwardly, so that the hooks c^2 will catch upon the upper edge of the bilge truss hoop. The main shaft is now moved longitudinally in the direction to bring the wheel W' in contact with the friction-wheel X , and thereby revolve the screw E in the direction to run the head-piece c (and thereby the drivers) downwardly a distance to bring the required strain upon the truss-hoop. The drivers are then released of their hold by a movement of the

disk and expanding-arms. Then the quarter-hoop is put on and driven in the same manner. The driving of these two (or more) hoops has also pressed the barrel into the under-head hoop, so that the barrel is now ready to croze on one end. The ring K , by reason of the ends of the staves resting thereon, will hold them perpendicular, and prevent them, or either of them, from slipping out of place while the power is applied. Any amount of power which the staves or the truss-hoops are able to bear may in this manner be applied. The truss-hoops being thus driven, and the staves pressed as tightly together as required, the wedge L is withdrawn sufficiently to allow the ring K to drop away from the staves and make room for the free working of the chamfering, crozing, and howeling tools. This being done, the tool-head M , which carries the chamfering, crozing, and howeling tools, is put into motion and revolved with great rapidity, and the operator, by means of the arrangement of the pinion S , incline shaft S' , wheel nut R , vertical shaft Q , cross-head P , and hinged arms O , can bring the said tools gradually to their work with such depth of cut as the work will bear. The chamfering, howeling, and crozing is done in one operation in a most perfect and satisfactory manner. The barrel is then turned end for end and the same process repeated.

Having now described the construction and operation of my improved machine, what I claim therein as new, and desire to secure by Letters Patent, is—

1. Driving hoops on barrels and other casks by power applied to yielding or flexible drivers, substantially as described.
2. The ring K , or equivalent, on which the barrel stands while the hoops are being driven, and which may be moved out of the way for the operation of the chamfering, crozing, and howeling tools, as set forth.
3. The arms D , in connection with the disk D' , or equivalents, for the purpose of expanding and contracting the drivers, as set forth.
4. The outer revolving hollow shaft, T , which carries the chamfering, crozing, and howeling tools, in combination with an inner shaft which has a vertical movement, for the purpose of imparting a lateral movement to the said tools or either of them.

5. Regulating the depth of cut of the chamfering, crozing, and howeling tools, or either of them, by means of a vertical movement of a shaft, nut, or head-piece to which the said tools, or either of them, are in any manner connected.

6. The construction and use of a hoop-driving machine and a barrel chamfering and crozing machine in one machine, for the purposes and substantially as described.

EDWARD HOLMES.
